UNITED STATES PATENT OFFICE

1,943,292

ILLUMINATING PROJECTILE

Herbert S. Babbitt, Baldwin, N. Y., assignor to
the Government of the United States,
represented by the Secretary of the Navy

Application March 11, 1926. Serial No. 94,092

9 Claims. (CL. 102—24.1)

(Granted under the act of March 3, 1883, as
amended April 30, 1928; 370 O. G. 757)

My invention relates to improvements in illuminating projectiles.

An object of my invention is to provide an improved projectile of the character described that 5 will be more reliable and efficient in use and operation.

Another object is to provide a simple and practical illuminating projectile that may be inexpensively manufactured and assembled.

10 A further object is to provide a practical illuminating projectile involving the use of a single parachute that will act not only to retard the illuminant or charge when ejected from the rear of the projectile but also to sustain the same 15 after it has been released and retarded.

By way of further explanation of the objects sought to be accomplished by the present invention, it may be stated that previous standard types of illuminating projectile contents were as 20 follows:

(1) An illuminant container or pot supported by three or more parachutes on a common cable (multiple-parachute type.)

(2) An illuminant container or pot supported 25 by a single parachute on a suspension cable, and with special center cable retarding arrangement (Martin suspension-cable single type.)

It may be further explained that neither of the preceding standard types named was found satisfactory in operation because the suspension cable would become twisted and kinked, and fouled with other parts of the mechanism, due to the spinning and tumbling actions at ejection, and so prevent or limit proper suspension. In the 35 present invention, this twisting and fouling tendency due to spinning and tumbling actions of the contents at ejection, are overcome.

Reference is to be had to the accompanying drawings forming part of this specification, in 40 which like reference characters indicate corresponding parts throughout the several views, and in which

Figure 1 is a vertical longitudinal sectional view of the complete assembled shell,

45 Figure 2 is a view of the shell or projectile at the moment of release,

Figure 3 is a detailed view of the parachute and suspended light several moments after release.

Figure 4 is a detailed sectional view of the star 50 or light.

Figure 5 is a detailed view of the top of the parachute,

Figure 6 is a bottom plan view of Figure 4,

55 Figure 7 is a plan view of the top of the para-

Figure 8 is a detailed view of the release wire, Figure 9 is an enlarged detail view of the star or light suspension,

Figure 10 is an enlarged detailed view of part 60 of the parachute construction, and

Figure 11 is a detailed view of the shroud swivel.

Referring more particularly to the drawings, 10 indicates the main body of a projectile of any desired caliber provided at its forward end with a fuse 11 preferably of the time variety, and rotating band 12.

The base of the projectile is provided with a removable cap 13 held in place by longitudinally disposed pins 14 and transverse shear pins 15.

Within the projectile at 70 the forward end is a chamber 16 containing the expellant charge adapted to be ignited by the time fuse.

This chamber is closed by a baffle 17 having one or more perforations 18 that allow the flame from the expellant charge to pass 75 through the baffle to ignite the illuminating material contained within the charge 20.

This is shown in Figure 4. This charge comprises a substantially cylindrical container 21 provided with a swivel connection 22 at one end.

A release wire 23 passes through this swivel connection, as well as a tubular member 24 that is notched 80 or roughened, as at 25, the better to hold the illuminating material contained therein.

The lower part of the release wire 23 is provided with a fusible knob 26 that melts after a predetermined time interval allowing the wire 23 to be withdrawn through the tube 24.

This arrangement and construction holds the parachute in partially opened position, as shown in Figure 2, 90 until its speed is materially reduced, but when the fusible knob is melted, the wire 23 is withdrawn allowing the parachute to open to full position, as shown in Figure 3.

The parachute 27 is carefully rolled and housed within the base 95 of the projectile, as shown in Figure 1, and is surrounded by two semi-cylindrical parts 28, immediately above which are two semi-discs 30 for holding two other semi-cylindrical parts 31 enclosing the charge container.

The powder charge within the container consists of two compositions, the A composition being designed to burn a predetermined time before the parachute is released, and the B composition being designed to burn a desired length of time 105 after the parachute is in full open position.

Powder pellets 37 are embedded in the composition and are supported by filling disks 40 having a plurality of openings therethrough. A surface or igniting powder 42 is placed in these openings.

The contents of the container are held therein by a cover 38, also provided with openings that align with the openings in the filling disks. A baffle gasket 41 is positioned between the baffle plate 17 and the container 21.

The suspension wires 33 of the parachute 27 are connected to the shroud wires 34 by swivel connections 35. The shroud wires pass around and are secured to shroud wire thimbles 43, the two terminals of each respective wire being secured to the swivel connections 35 on the earings or suspension wires that are at points laterally opposite across a common diameter of the parachute awning. The terminals of the shroud wires are passed through the wall of shroud sockets 44, frayed, and then solder applied to the ends, forming heads within the sockets. The sockets are connected to the suspension wires by thimbles 45. The thimbles about which the shroud wires are passed are connected to the swivel connection 22. It will thus be seen that the shroud wires have a swivel connection with the charge container and each of the said wires is also connected to the suspension wires by a swivel, which arrangement reduces to a minimum the possibility of entanglement of the various wires during release of the parachute. The release wire 23 is also attached to the parachute awning by a swivel connection 32, and passes through swivel connection 22 to be attached to the fusible knob, as above explained. It will be noted from Figures 3 and 10 that the suspension wires of the parachute are continuously reaved back and forth and up and down as indicated at 33 and connected with the shroud wires 34 by the swivels. The wires 33 passing over the parachute overlie reinforcing bands 36.

It will be clear to those familiar with the subject that when a projectile is fired it receives a high rate of rotation, which rotation is imparted to the parachute and its suspended light, and is maintained even after the parachute has been ejected. It is, therefore, highly desirable that means be provided for preventing the parachute and associated wires, lights, etc., from becoming snarled at the moment of release. The swivels above described effectively provide this prevention.

The invention herein described may be manufactured and used by or for the Government of the United States of America for governmental purposes, without the payment of any royalties thereon.

What I claim is:—

1. In an illuminating projectile, in combination, an assembly adapted to be ejected rearwardly from the projectile body, such assembly comprising a parachute, an illuminating element supported by the parachute, shrouds, and swiveling members connecting the shrouds to the parachute.

2. In an illuminating projectile, in combination, an assembly adapted to be ejected rearwardly from the projectile body, such assembly comprising a parachute, an illuminating element supported by the parachute, shrouds, and independent swivel elements connecting each of the shrouds to the parachute.

3. In an illuminating projectile, in combination, an assembly adapted to be ejected rearwardly from the projectile body, such assembly comprising a parachute, an illuminating element

supported by the parachute, shrouds, sockets carried by the parachute awning, and means for providing a rotatable connection of the shrouds with the sockets.

4. In an illuminating projectile, in combination, an assembly adapted to be ejected rearwardly from the projectile body, such assembly comprising a parachute, an illuminating element supported by the parachute, sockets carried by the parachute awning, shroud wires, and soldered terminals on said wires housed within the sockets to permit rotation of the wires in the sockets. 80

5. In an illuminating projectile, in combination, an assembly adapted to be ejected rearwardly from the projectile body, such assembly comprising a parachute, an illuminating element supported by the parachute, swivel members connected to the parachute awning at laterally opposite points across a common diameter of the parachute, and a plurality of continuous shroud wires having their ends connected to the swivel members. 85 90 95

6. In an illuminating projectile, in combination, an assembly adapted to be ejected rearwardly from the projectile body, such assembly comprising a parachute, an illuminating member supported by the parachute, a swivel at the top eye of the parachute, and a releasable wire connecting the illuminating member and swivel. 100

7. In an illuminating projectile, in combination, an assembly adapted to be ejected rearwardly from the projectile body, such assembly consisting of a container, flare compositions within the container, powder pellets embedded in one of the compositions, a filling disk having openings therethrough and supporting the compositions, an igniting powder in said openings contacting with the pellets, and a cover over said disk having openings aligning with those in the disk, a parachute, and means attaching the container to the parachute. 105 110 115

8. In an illuminating projectile, in combination, an assembly adapted to be ejected rearwardly from the projectile body, such assembly comprising a parachute, an illuminating member consisting of a container, a plurality of flare compositions within the container, a serrated member within the container about which the compositions are placed, powder pellets embedded within one of the compositions, a filling disk, igniting powder carried by the disk, and a cover for the container, and means for attaching the container to the parachute. 120

9. In an illuminating projectile, in combination, an assembly adapted to be ejected rearwardly from the projectile body, said assembly comprising a parachute, an illuminating member including a container, a plurality of flare compositions within the container, a swivel in the wall of the container, a hollow member within the container about which the compositions are placed, a fusible member within said hollow member, powder pellets embedded in one of the compositions, a filling disk having openings therethrough and supporting the compositions, 125 an igniting powder in the openings contacting with the pellets, and a cover over said disk having openings aligning with those in the disk, means connecting the fusible member with the parachute, and means attaching the container to the parachute. 130 135

10. In an illuminating projectile, in combination, an assembly adapted to be ejected rearwardly from the projectile body, such assembly comprising a parachute, an illuminating member including a container, a plurality of flare compositions within the container, a swivel in the wall of the container, a hollow member within the container about which the compositions are placed, a fusible member within said hollow member, powder pellets embedded in one of the compositions, a filling disk having openings therethrough and supporting the compositions, 140 an igniting powder in the openings contacting with the pellets, and a cover over said disk having openings aligning with those in the disk, means connecting the fusible member with the parachute, and means attaching the container to the parachute. 145

HERBERT S. BABBITT.
